DESIGN FOR A COCKTAIL SHAKER OR SIMILAR ARTICLE

Albert L. Davis, Watertown, Conn., assignor to
The American Brass Company, Waterbury,
Conn., a corporation of Connecticut

Application September 5, 1935, Serial No. 58,447

Term of patent 7 years

To all whom it may concern

Be it known that I, Albert L. Davis, a citizen of the United States, residing at Watertown, county of Litchfield, State of Connecticut, have invented a new, original, and ornamental Design for a Cocktail Shaker or Similar Article, of which the following is a specification, reference being had to the accompanying drawing, forming part thereof.

The figure is a side elevational view of a cocktail shaker, showing my new design.

The contour of the article is substantially circular.

I claim:

The ornamental design for a cocktail shaker or similar article, substantially as shown and described.

ALBERT L. DAVIS.
